COSTUMER

Edmond J. Forsyth, Chicago, Ill.

Application August 28, 1939, Serial No. 292,201

6 Claims. (Cl. 211—178)

This invention relates to furniture and more particularly to costumers or clothes trees.

The object of the invention is to provide a novel, ornamental and attractive costumer particularly designed for children's rooms and use, in which the base and garment supporting top portion simulate various animals and, at the same time, form a part of the structure of the costumer.

A further object is to provide a children's costumer in which the top and base portions are assembled in a novel manner in conjunction with a standard so that the device can be readily assembled or disassembled and stored in a compact space, but which, when in use, will be substantially rigid, strong and durable.

Other objects and advantages will appear hereinafter, reference being had to the accompanying drawings; wherein:

Fig. 1 is an elevation or face view of the costumer;

Fig. 2 is a similar view at right angles to Fig. 1;

Fig. 3 is a horizontal section taken on the line 3—3 of Fig. 1;

Fig. 4 is an enlarged horizontal section taken on the line 4—4 of Fig. 1;

Fig. 5 is a detail of a clamping bolt employed;

Fig. 6 is a top plan view of the device;

Fig. 7 is an enlarged horizontal section taken on the line 7—7 of Fig. 1;

Fig. 8 is a face view of one top or hanger element;

Fig. 9 is a face view of one bottom or base element;

Fig. 10 is a face view of one other top or hanger element;

Fig. 11 is a face view of one other bottom or base element;

Fig. 12 is an elevation of the standard or upright;

Fig. 13 is an opposite elevation of the standard or upright;

Fig. 14 is an elevation of the standard or upright folded; and

Fig. 15 is an enlarged section of the hinge joint or connection between the sections of the standard.

Referring to the drawings, the costumer comprises a base 20 made up of two sections consisting of a bottom section 21 and a top section 22 simulating two opposed animals arranged back to back and shown in the form of elephants 23 cut from sections of composite board, ply wood, veneer wood or other suitable material. Con-

necting the two opposed animals facing in opposite directions in a unitary piece is an intermediate, narrow, connecting portion or section 24 having a recess 25 at the bottom and a recess 26 at the top. Extending from the center and bottom edge of the recess 26 is a vertical slot 27 which is provided in the bottom section 21. The top section is correspondingly formed except that the slot 28 extends vertically and upwardly from the center of the bottom recess 25 so that the section 22 will accommodate the lower portion of the wall 24 of the section 21 in the slot 28 while the upper portion of the wall 24 of the section 22 will be accommodated in the slot 27 when the sections are joined by moving them relatively one over the other in sliding telescopic fashion normal to each other so as to form a cross-shaped piece. Each section 21 and 22 is provided with a hole 29 adjacent its slot.

A standard 30 forms an upright for the costumer and is of a foldable or collapsible structure including a lower section 31 and an upper section 32 which may be of rectangular or other cross section. These sections have their ends abutting as shown at 33 and are joined by oppositely disposed hinges 34 secured by screws 35 so that by removing the screws of one hinge leaf, the sections may be folded on each other as shown in Fig. 14 of the drawings. Obviously a rigid plate may be substituted for one hinge or any other desired form of connection between the standard sections provided. The lower end of the standard or section 31 is provided with slots 36 and 37 running longitudinally between opposite sides and intersecting each other at right angles. Holes 38 are provided at one side and near the upper end of the slot 37 and near the lower end of the slot 36 adapted to take bolts 40 when these slotted ends are fitted over the sections 21 and 22 as shown in Figs. 1-4, inclusive, of the drawings so as to pass through the holes 29 and rigidly secure the base sections to the standard or vice versa and perpendicularly to each other to form a substantial support for the costumer. Cap nuts 41 are applied to the ends of the bolts to clamp the parts in position.

Corresponding, but slightly longer intersecting slots 42 and 43 are provided in the upper ends of the upper section 32 of the standard with holes 44 at each side of one slot shown as the slot 42 and parallel to each other to take similar bolts 40 for clamping the upper or suspension section of the costumer to the standard. This suspension section includes a bottom portion 45 and an upper portion 46 formed in the same manner as the

sections 21 and 22 but shown simulating other animals such as monkeys, as shown at 47 so that the heads 48 form hat racks and the tails 49 form hooks while the bodies of the animals are connected by the fore and hind legs, portions thereof constituting parts of narrow connecting portions 50 between the two animals which, in this instance, are disposed to face each other with their legs outstretched and their paws together. The section 45 is provided with an upper slot vertically and centrally as indicated at 51 and the section 46 is provided with a corresponding bottom slot 52 whereby these sections may be telescopically fitted one over the other, the same as the base forming sections with the ends of the slots limiting the relative displacement or sliding movement of one section on the other also the same as with the base sections and with the ends of the slots in contact. The section 46 is provided with two holes 53 to register with the holes 44 and the section 46 is provided with a top extension 54 on the central section or connecting portion 50 also representing an animal and shown as a monkey. The bottom section 45 has a slot 55 communicating with and intersecting the slot 51 severing the fore legs from the central section 50 and a corresponding slot 56 is provided in the section 46 separating the hind legs from the corresponding connecting or central section 50 thereof and intersecting or communicating with the slot 52. When the sections 45 and 46 are assembled in the manner described, they are slid down into the intersecting slots 42 and 43 which are disposed at right angles to each other in the upper end of the section 32 of the standard and connected by the bolts 40 disposed through the registering holes 44 and 53 to rigidly connect these parts. The bolts prevent the displacement of the upper section 46 and the lower section 45 is held by the interlocking engagement with the section 46 from upward displacement. However, the parts may be readily disconnected as well as set up for use and when disassembled, all of the sections 21, 22, 45 and 46 being flat, may be compactly stored together with the foldable or collapsible standard forming the upright portion of the costumer.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent, is:

1. In a costumer of the class described comprising a sectional base, a standard connected to the same and comprising two hinged sections and a suspension section at the top of the standard, the standard having intersecting slots at the top and bottom and the base and suspension sections each comprising flat members having narrow con-

nected portions with top and bottom slots telescopically interfitting in the slots of the standard, and connecting means through the standard and base and suspension section members.

5. In a costumer of the class described comprising a sectional base, a standard connected to the same and a suspension section at the top of the standard, said base and top sections comprising intersecting flat members interlocked to each other and connected to the standard, one of said members being held to the standard by the connecting means of the other member.

10. In a costumer of the class described, comprising a sectional base, a standard connected to the same and a suspension section at the top of the standard, said base and top sections each comprising slotted members interfitting at right angles to each other, means for connecting the base members to the standard and means for connecting a top member to the standard to prevent displacement thereof, said connecting means each comprising bolts and said standard and certain of said slotted members having registering holes to take the bolts therethrough to clamp said parts together.

15. In a costumer of the class described including a foldable standard having slots at its ends, a base including intersecting and interfitting members separably connected and fitting the slots at the bottom of the standard, connecting means between the bottom members and the standard and extending through the same, a suspension section comprising interfitting separably connected members disposed in intersecting relation and received in the top slots of the standard and means for connecting at least one member of the base and suspension section to the standard and extending through the same.

20. In a costumer including a standard comprising hinged sections disposed coextensively with each other and adapted to be folded one on the other, a base slidably fitted in the lower end of the lower section of the standard and comprising intersecting flat members, means for anchoring the base through and to the standard, an upper garment supporting portion including flat members having hook portions and disposed in intersecting relation and slidably fitted in the upper end of the standard, and means for anchoring the garment supporting portion through and to the standard.

25. In a costumer of the class described including a base portion, a standard thereon, and a hanger portion at the top of the standard, portions comprising members disposed in intersecting interlocked relation and connected to each other and to the standard through the latter, said base portion and hanger portion each comprising two oppositely disposed intersecting flat members with narrow connecting portions therebetween having top and bottom slots, the connecting portion of certain of said members being severed from other portions of the members across the slots and one of said members being held in position by the other through the medium of the connecting means with the standard.

EDMOND J. FORSYTH.
